UNITED STATES PATENT OFFICE.

GEORGE COUSINS, OF OSWEGO, NEW YORK.

STAYBOLT-CHUCK.

1,393,267.

Specification of Letters Patent. Patented Oct. 11, 1921.

Application filed December 23, 1920. Serial No. 432,736.

To all whom it may concern:

Be it known that I, GEORGE COUSINS, a citizen of the United States, and a resident of Oswego, in the county of Oswego and State of New York, have invented certain new and useful Improvements in Staybolt-Chucks, of which the following is a specification.

My present invention relates generally to the manipulation of stay bolts in screwing the same in and removing the same from operative position wherever used, it being a well known fact that short projections are invariably left which may, by the use of an implement proposed by my invention, be effectively engaged and, by application of manual or power connections to the implement, the stay bolt may be turned inwardly or outwardly depending upon the direction of application of the power.

The object of my invention is the provision of an effective, strong and durable implement in the nature of a chuck, by which to engage and rotate a stay bolt in either direction and with equal efficiency, and a still further object is the provision of an implement in the nature of a chuck in which the stay bolt engaging jaws may be readily adjusted and actually forced into operative connection with the projecting portion of a stay bolt.

Still further objects, including the provision of stay bolt engaging jaws of readily renewable, adjustable and interchangeable nature insuring long, active and efficient life, will be better understood from the following detailed description of the invention, in which reference is made to the accompanying drawings, forming a part of this specification, and wherein,

Figure 1 is a rear elevation of my improved chuck,

Fig. 2 is a top plan view thereof, partly broken away and in section,

Fig. 3 is a sectional rear elevation of the face plate of the chuck of Figs. 1 and 2,

Fig. 4 is a view similar to Fig. 3 showing a slightly modified arrangement of adjusting slots,

Fig. 5 is a front elevation of the jaw forming means showing the same in normal position,

Fig. 6 is a view similar to Fig. 5 showing

the jaw forming members adjusted to engage a stay bolt of small diameter, and 55

Fig. 7 is a detail section taken on line 7—7 of Fig. 1.

Referring now to these figures I have shown my improved implement as comprising a preferably circular face plate 10 from the central rear portion of which projects a rearwardly extending shank 11, in the present instance shown as a taper shank, but which may of course be simply a squared extending shank, depending upon whether it is to be used with power or manually actuated connections. In any event this shank preferably has an enlarged annular portion or collar 12 spaced from the rear surface of the face plate 10, and around which an adjusting plate 13 is centrally mounted to rotate. This adjusting plate has diametrically outstanding arms 14 and diametrically opposed extensions 15, the latter at right angles to the arms 14 and provided with 75 lengthwise slots 16.

Between the adjusting plate 13 which rotates around the shank collar 12 and the rear surface of the face plate 10 is a two-part liner or connecting plate 17, whose inner 80 portions extend inwardly beyond and lap the collar 12, the two parts of this liner or connecting plate following in contour that of the adjusting plate 13 except that the diametrically opposed slots 18 thereof are 85 somewhat narrower than the slots 16 of the adjusting plate and the liner or connecting plate terminates intermediate the ends of the arms 14 of the adjusting plate as indicated by the dotted lines in Fig. 1. The two 90 parts of the connecting plate or liner 17 are connected to the adjusting plate 13 by screws and the like 19, which serves to hold the two parts of the liner in proper position whereby it functions to prevent rearward movement of the adjusting plate with respect to the face plate 10 owing to the engagement with collar 12 of the shank. 95

The jaw forming means shown in Figs. 5 and 6 are disposed at the front surface of 100 the face plate as seen in Fig. 2 and consists of a series of notched straight arms 20 and 21, whose ends are apertured for the reception of pivot pins 22 and 23, pins 22 having inner heads 24 abutting the front surface of 105 face plate 10 and pins 23 having heads 25

and inwardly projecting stems 26, the latter mounted through cam slots 27 of the face plate and provided with heads 28 at their inner ends movably seated in the slots 16 of adjusting plate 13 and with reduced neck portions 29 adjacent to the heads 28 and seated in the slots 18 of the liner or connecting plate 17.

The arms 20 and 21 of the jaw have 10 toothed inner and outer surfaces 30 and 31 and these arms, provided as they are with squared ends, are joined in endwiselapping relation to form an adjustable rectangular jaw in which the arms 20 occur at opposite sides and singly while the arms 21 occur at the other opposite sides in spaced parallel relation to receive between the ends thereof, the ends of the arms 20. The pivot pins 22 and 23 extend loosely through end 20 apertures of the arms 20 and 21 and are provided at the forward face of the jaw with washers 32 and held in place by cotter pins 33, upon removal of the latter and the washers, it becomes quite obvious the several 25 toothed arms may be removed and replaced in interchanged relation to bring new unused portions of their toothed edges to the effective inner side of portion of the jaw.

In Figs. 1 and 3 I have shown the cam 30 slots of the face plate 10 so arranged that the stems 26 of the pins 23 are disposed centrally between the ends of the slots in their innermost positions at the inner ends of the slots 16 of the adjusting plate 13, the 35 jaw being in this position of the square form of Fig. 5 and in position to receive the largest diameter of stay bolt 34 which the chuck is designed to operate upon. By grasping the arms 14 of the adjusting plate and rotating the adjusting plate in either direction, the pivot pins 23 will be shifted outwardly away from one another, causing inward movement of the pins 22 and thus bringing about adjustment of the jaw to engage a stay bolt 35 of comparatively small diameter as in Fig. 6, it being obvious that by means of this adjustment the inner toothed faces of the jaw arms are actually and positively pressed into engagement with 50 the stay bolt surface.

Instead of the slots 27 shown in Figs. 1 and 3, the face plate may be provided with offset arcuate slots 36 as in Fig. 4 on the face plate 10, it being obvious that slots of this 55 and other form are adapted to act in the nature of cams in connection with the adjustment of the jaw through manipulation of the adjusting plate 13 and that still other and differently formed slots may be utilized 60 for this purpose.

In order to bring the jaw back to its normal position shown in Fig. 5, brackets 37 may be disposed between and pivotally connected to the spaced pairs of arms 21, to 65 serve as anchors for flat springs 38, con-

nected to the brackets by screws 39, and having free ends bearing against the square extremities of the arms 20 so that as the jaw is adjusted to the position of Fig. 6, the opposite ends of the springs will be flexed and 70 the springs thus placed under tension so that when the jaw is subsequently released from the work, the springs will act to return the same to the position of Fig. 5.

It will also be noted by reference to Figs. 75 5 and 6 that the inner toothed edges 30 of the jaws are so arranged that the jaws 20 grip the work upon rotation of the chuck in one direction while the jaws 21 grip the work upon rotation of the chuck in the opposite direction.

If so desired the face plate 10 may be provided with a concave recess 40 at one point in its rear edge, to receive the inner conical end of a screw 41 threaded through 85 one of the arms 14 of the adjusting plate 13 so that the jaw may be retained by this means in the normal position shown in Fig. 5, with just sufficient effectiveness to support the same while this jaw is being applied over the projecting portion of a stay bolt and before the jaw is actually adjusted into effective engagement with the stay bolt for manipulation of the adjusting plate.

By thus providing for effective engagement of a stay bolt and for rotation of the chuck either through power connections such as an electric drill or manually through the use of a socket or other wrench, and more particularly by the provision of the 100 adjustable interchangeable jaw forming arms 20 and 21 with their toothed inner and outer surfaces, I propose an implement which will be effective and efficient in use for the intended purposes and will be strong 105 and durable.

I claim:

1. A chuck of the type described including a face plate having cam slots, jaw forming members consisting of toothed arms in 110 endwise overlapping relation at the front surface of the face plate, pivot pins extending through the overlapping ends of the jaws and certain of which pins are extended rearwardly through the cam slots of the face 115 plate, and means adjacent to the rear surface of the face plate and engaging the said extended pivot pins for shifting the latter in the face plate slots.

2. A chuck of the type described including a face plate having cam slots, jaw forming members consisting of toothed arms in 120 endwise overlapping relation at the front surface of the face plate, pivot pins extending through the overlapping ends of the jaws 125 and certain of which pins are extended rearwardly through the cam slots of the face plate, and means adjacent to the rear surface of the face plate and engaging the said extended pivot pins for shifting the latter 130

- in the face plate slots, said last named means including an adjusting plate provided with slots receiving the extended pivot pins and rotatably supported in connection with the 5 face plate.
3. A chuck of the character described comprising a face plate having an axial shank at its rear face and provided with cam slots, an adjusting plate rotatably 10 mounted on the shank adjacent to the rear surface of the face plate and having radial slots, and a jaw at the front surface of the face plate, said jaw including a series of arms having toothed edges and overlapping 15 ends, and pivot pins connecting the said overlapping ends of the arms, certain of which are extended rearwardly through the face plate slots and into the slots of the adjusting plate as described.
- 20 4. A chuck of the character described including a face plate and an article engaging jaw on the face plate comprising a plurality of arms having toothed edges and overlapping ends, pivot pins extending through the 25 said overlapping ends and upon which the arms are removably supported, certain of said pins having adjustable connection with the face plate and means for adjusting the pins on the face plate as described.
- 30 5. A chuck including a face plate having cam slots and a rearwardly projecting axial shank, a jaw at the front surface of the face plate including toothed arms having overlapping ends, pivot pins extending through 35 said ends and detachably connecting the arms, certain of which pivot pins are extended rearwardly through the cam slots of the face plate, and an adjusting plate rotatably disposed at the rear of the face plate and
- having means to movably engage the said 40 shank and the rear ends of said projecting pivot pins.
6. A chuck including a face plate having cam slots and a rearwardly projecting axial shank, a jaw at the front surface of the face 45 plate including toothed arms having overlapping ends, pivot pins extending through said ends and detachably connecting the arms, certain of which pivot pins are extended rearwardly through the cam slots of the 50 face plate and are provided with rear heads, an adjusting plate rotatable at the rear surface of the face plate and having slots in which the rear heads of said pivot pins are disposed, and a connecting plate disposed 55 between the adjusting plate and the face plate, said connecting plate being secured to the adjusting plate and having means to movably engage the said extended pivot pins and the shank of the face plate for the purpose described.
7. A chuck of the character described including a jaw having a series of arms provided with toothed inner and outer edges and with overlapping ends, pivot pins extending 65 through the said overlapping ends and with respect to which the toothed arms are removably held, means for supporting and adjusting said pivot pins said arms having square ends, and springs carried by certain 70 of the arms, having free ends engaging the square ends of the other arms to normally hold the arms in right angular relation.

GEORGE COUSINS.
